UNITED STATES PATENT OFFICE.

WILLIAM C. KEWIN, OF ROCHESTER, NEW YORK.

CUFF-HOLDER.

SPECIFICATION forming part of Letters Patent No. 707,427, dated August 19, 1902.

Application filed August 5, 1901. Serial No. 70,977. (No model.)

To all whom it may concern:

Be it known that I, WILLIAM C. KEWIN, of Rochester, in the county of Monroe and State of New York, have invented a new and useful Improvement in Cuff-Holders, which improvement is fully set forth in the following specification and shown in the accompanying drawings.

My invention is an improved cuff-holder, simple in form and comparatively inexpensive in matter of construction and designed particularly with reference to simplicity and convenience in operation, the same being hereinafter fully described, and more particularly pointed out in the claims.

While this device may be conveniently secured to the sleeve of the shirt for the purpose of holding the cuff, it may also be readily secured to the lining of the sleeve of the coat and is shown in the drawings adapted to be used in that manner.

Aside from the convenience and ease with which this device may be used, one of the objects of the invention is to produce a cuff-holder which permits of the cuff being readily shifted longitudinally within the sleeve and held at any desired position relative therewith.

Referring to the drawings, Figure 1 shows the outer face of the device full size. Fig. 2 shows the reverse or inner face. Fig. 3 is an edge view of the holder seen as indicated by arrow 3 in Fig. 2, the adjacent part of the cuff being longitudinally sectioned and the catch-piece shown in two positions by full and dotted lines. Fig. 4, drawn to a scale double in size, is a longitudinal section of the body of the device, taken as on the dotted line 4 in Fig. 3 and viewed as indicated by the arrow pointed thereon. Fig. 5, also double in size, is a central longitudinal section of the body of the device and associated parts, taken as on the dotted line 5 in Fig. 1. Fig. 6, drawn to a scale full size, shows the application of the device to a cuff.

A is the body of the device, commonly made of thin sheet metal bent to form and properly shaped.

B is the catch-piece for seizing the cuff, held to the body A by a transverse pindle a, upon which the catch-piece is adapted to turn, as indicated in Fig. 3. This catch-piece, also

usually formed of sheet metal, is held between parallel upturned flanges b b of the body near one end, the hollow sides of the body and the catch-piece being turned toward each other, forming an inclosure, in which is placed a spring c, coiled about the pindle a. The terminals d e of the spring extend out some distance from the coil in position to press outward against the opposing surfaces of the body and the catch-piece, respectively, tending to spread said parts or push them apart. The catch-piece is formed with a downwardly or inwardly turned catch f, adapted to meet and press the adjacent side of the body A, as shown in the various figures, said inturned part f being preferably serrated or toothed to better hold the cuff, the spring acting on one side of the pindle a to spread the catch-piece, and the body causes the part f on the other side of the pindle to press the body, and so firmly grip the part of the cuff inserted beneath it, as shown in Figs. 3 and 6, the catch-piece acting as a lever.

The elongated hollow body A of the device is formed at the side opposite from the catch-piece with a notch or opening g, Figs. 1, 3, and 5, opening into the interior of the body. A slide h is provided to move longitudinally within the body, a part projecting through the end of the body and formed at its outer free end with an upturned part i, to be caught by the thumb-nail in drawing the slide outward or to the position shown in Figs. 4 and 5. This slide is shown as doubled or turned back upon itself, and it holds rigidly a pin k in position to centrally cross the opening g just within the adjacent side or wall of the hollow body A. The slide is made of elastic material, as hard metal, its two overlapping sections or parts l n tending to open out or spring away from each other, crowd the interior of the body, and constitute a friction tension for the slide, causing it to hold to place in any position it may occupy within the body. One member n of the bent slide is longer than the other member l and extends out at the end of the body, as shown in Fig. 5. The short member l is confined within the body, the latter having an extreme upturned part o, which, opposing the part l, constitutes a stop for the slide to control the latter and prevent it from being drawn out of

the body. When the slide is drawn outward against said stop *o*, the point of the pin *k* is about even with the adjacent edge of the opening *g*, as shown. When the slide is 5 pressed inward, the upturned part *i*, meeting the end of the body, constitutes a stop for the slide in that direction.

In using the cuff-holder it is first caught onto the outer end of the cuff *C* by means of 10 the catch-piece *B*, as shown in Fig. 6, said catch-piece being opened or turned back by pressing with the thumb and finger the extreme even ends of the catch-piece and the body *A*. The cuff is then inserted in the 15 coat-sleeve and a part *D* of the sleeve pressed by the end of the thumb into the opening *g*, as appears in Fig. 5, the slide *h* having been first drawn outward to remove the pin from said opening. An inward pressure of the finger 20 against the extreme end or part *i* of the slide causes the pin to pierce the opposing part of the sleeve pressed into the opening, thus securely attaching the holder to the sleeve. When the slide is pressed inward, 25 as stated, to bring the thumb-piece *i* against the end of the body *A*, as appears in Figs. 1 and 6, the pin completely crosses the opening *g* longitudinally, the point of the pin passing in above the spring, so as to have a bearing 30 against the inner surface of the adjacent wall of the body over the spring. This affords a support for the pin on both sides of the opening and the part of the fabric through which the pin passes.

35 What I claim as my invention, and desire to secure by Letters Patent, is—

1. A cuff-holder comprising an elongated hollow body formed with an opening, and with parallel flanges near one end, a catch-piece 40 shorter than the body held longitudinally between said flanges, and a transverse pintle in the body piercing the catch-piece, with means for turning the latter on said pintle to engage the body, and a pointed shaft or pin 45 adapted to move longitudinally in the body adjacent to said opening in the latter, substantially as and for the purpose specified.

2. A cuff-holder comprising a hollow body having an opening in its side, a pivotal catch-

piece held by said body, a sliding piece or 50 slide adapted to move longitudinally within the body, a pin carried by said slide to cross said opening in the body, and means for actuating the catch-piece, substantially as shown and described.

3. A cuff-holder comprising a hollow body formed with a side opening, a pin adapted to move longitudinally in said body to cross said opening, parallel flanges on the body carrying a transverse pintle, a catch-piece held 60 pivotally on said pintle, and a spring controlled by said pintle, with its extreme ends pressing the catch-piece and said body respectively, substantially as and for the purpose specified.

4. A cuff-holder having a body formed with an opening, a catch-piece held pivotally by said body and adapted to engage the latter, a pin adapted to slide longitudinally within the body adjacent to said opening, and means for 70 turning said catch-piece against the body, the catch-piece and said opening being on opposite sides of the body, substantially as shown and described.

5. A cuff-holder comprising a hollow body 75 formed with an opening, a pivotal catch-piece held by the body, a slide adapted to move longitudinally in said body, a pin carried by the slide to cross said opening in the body, and stops to limit the longitudinal motions 80 of said slide, substantially as set forth.

6. A cuff-holder comprising a hollow body formed with an opening, a pivotal catch-piece held by the body, a slide adapted to move longitudinally in said body, a pin carried by 85 the slide to cross said opening in the body, the slide being bent transversely or doubled with ends of unequal length, the longer one projecting from the body and the other confined within the body, substantially as shown 90 and described.

In witness whereof I have hereunto set my hand, this 2d day of August, 1901, in the presence of two subscribing witnesses.

WILLIAM C. KEWIN.
